UNITED STATES PATENT OFFICE.

JOHN V. HOLSTEIN, OF MOLINE, ILLINOIS, ASSIGNOR TO DEERE AND COMPANY, OF MOLINE, ILLINOIS, A CORPORATION OF ILLINOIS.

TWO-ROW CULTIVATOR.

1,346,317.

Specification of Letters Patent. Patented July 13, 1920.

Application filed November 27, 1915, Serial No. 63,780. Renewed October 20, 1919. Serial No. 332,016.

To all whom it may concern:

Be it known that I, JOHN V. HOLSTEIN, a citizen of the United States, residing at Moline, in the county of Rock Island and State of Illinois, have invented certain new and useful Improvements in Two-Row Cultivators, of which the following is a specification, reference being had therein to the accompanying drawing.

10 My invention relates to cultivators and more particularly to that type of cultivators employed for treating the soil between rows of growing vegetation.

15 The objects of my invention are to simplify and improve the adjustable features of machines of this class so that any adjustment desired to facilitate proper cultivation can be quickly and easily secured. Other objects will be disclosed in the following specification:

20 Referring to the drawings in which similar numerals indicate identical parts—

Figure 1 is a plan view of my improved cultivator.

25 Fig. 2 is a front elevation.

Fig. 3 is a detail section on the line 3—3 of Fig. 1.

Fig. 4 is a rear elevation of one end of the cultivator.

30 Fig. 5 is an enlarged view of part of the adjusting mechanism.

Fig. 6 is an enlarged detail side elevation of part of the adjusting mechanism.

Fig. 7 is an enlarged detail of lever 35 mountings.

Fig. 8 is an enlarged detail section of part of the wheel control mechanism.

Fig. 9 is an enlarged detail of a rear arch connection to the tool beams.

40 Fig. 10 is an enlarged detail of a rear arch connection with the frame.

Fig. 11 is an enlarged detail of a connection of a lifting link and spring with a tool beam.

45 Fig. 12 is an enlarged detail of an end of a front arch showing brace connections.

The main frame comprises a front bar 1 and a rear bar 2 spaced apart and rigidly connected by end bars 3; cross bars 4, 5, 6 50 and 7 at suitable intervals extend between the bars 1 and 2 and are rigidly secured thereto. Brackets 8 are secured to the ends of the bar 2 and have vertical tubular bear-

ings 9 preferably integral therewith, supporting wheels 10 are journaled on the horizontal portions of crank axles having spindles 12 which are adapted to oscillate in the tubular bearings 9; collars 13 are loosely mounted on the spindles 12 below the tubular bearings 9. Draft poles 9^a are secured 60 in any suitable manner to the frame bar 1 and the cross bars 4 and 7.

To the upper end of the spindles 12 are rigidly secured forwardly extending arms 14. Secured on the bars 5 and 6 are standards 15 having slots or guideways 16 in which is slidably supported a bar 17, the latter having perforations at its extremities in which are secured in any suitable manner the ends of rods 18 which extend to the 70 arms 14 and have a threaded engagement with members 19 which are pivotally supported on the arms 14 by means of studs 20, preferably integral with the member 19, and which project through 75 openings in the arms 14 and are secured therein by pins or cotters 21. Central of the underside of the sliding bar 17 and attached thereto is a lug 22 to which is connected, preferably by its central link, 80 a chain 23 which is practically divided by the lug 22 into two portions 24 and 25; the portion 24 passes over a roller 26, mounted on a support 27 in the bar 5, and extends downwardly to a foot lever 28, the latter 85 being pivotally supported on a bracket 28^a on the bar 1 and having a treadle 29 mounted on its free end; the portion 25 of the chain 23 passes over a roller 30, mounted on a support 27^a on the bar 6, and extends 90 downwardly to a foot lever 31 which is pivotally supported on the bracket 28^a on the bar 1 and has a treadle 32 mounted on its free end. Secured to the bars 5 and 6 are seat bars 33 which are further supported 95 by brackets through which the seat bars 33 extend rearwardly, converging toward their rear ends and supporting thereon a seat 34.

It will be noted that the seat 34 is so situated that the treadles 29 and 32 are within 100 easy reach. The operative mechanism just described relates to adjustment of the wheels 10 so that the cultivator can be guided while in operation to prevent injury to the plant row and to insure proper stirring of the 105 soil adjacent thereto, for it is obvious that

pressure upon the treadle on the lever on the side to which it is desired the machine should move will rock that lever downwardly pulling down the portion of the chain 23 connected to it and the lug 22, this action will operate the bar 17 to slide in the guideways 16, and as the rods 18 are connected to the bar 17 and to the arms 14 on the spindles 12, the latter will be oscillated in 10 the bearings 9 to swing the wheels 10 in the desired direction.

Two groups of cultivator gangs are employed as shown in the drawings, and as both groups are mounted, operated, and 15 adjusted in a similar manner a description of one will suffice. Each group consists in this instance of two beams 35 having their forward ends loosely mounted to permit of a vertical rocking movement on horizontal 20 end portions 36 of an arch 37; the arch 37 is laterally movable, as will be hereinafter explained, and is supported by rods 38 having their upper ends bent to engage with eyes 39 mounted on the frame bar 2; the 25 lower ends of the rods 38 are bent to hook into eyes on collars 40 mounted on the horizontal portions 36 of the arch 37; similar eyes are formed on the forward side of the collars 40 for the reception of hook ends 30 of rods 41 which extend toward the frame bar 1 and have their ends bent to engage with a suitable perforation in said bar. I have shown cultivator shovels carried by the beams 35, but it is obvious that other 35 earth stirring devices can be substituted therefor.

Connected to the forward part of the beams 35 rearward of the connection of the latter to the arch 37 are coiled springs 42 40 the upper ends of which engage with eyes in bolts 43 rigidly attached to the rods 38 by clips 44. On the rear of the frame bar 2 is a rod 45 slidably mounted in brackets 46 secured to the frame bar 2; clamps 47 are 45 rigidly secured on the rod 45 and have slots 48 below the rod 45. A spreader arch 48^a composed of two members 49 and 50, each member having a vertical portion *a* and a horizontal portion *b*, is supported by the 50 clamps 47 by passing the portions *b* through the slots 48, one overlapping the other, and tightening the clamps by bolts *c*, the bottom of the clamps 47 being split for the purpose. The lower ends of the vertical portions *a* 55 project loosely through slots in clips 52 rigidly secured on the beams 35. By the use of an arch of this description the beams 35 of each group can be adjusted toward or from each other by loosening the bolts *c* in 60 the clamps 47 and moving the arch members 49 and 50 until the desired width between the beams 35 has been obtained when the bolts *c* are again tightened to hold the arch members 49 and 50 in their adjusted position; when this adjustment is made the

beams 35 will be drawn closer together or farther separated by the vertical arch portions *a* to adapt the cultivator for varying widths between rows of plants. As the beams 35 are moved by adjustment of the 70 arch portions *a* and *b*, the forward ends of the beams 35, being loosely mounted on the horizontal portions of the arch 37, can be moved laterally, agreeable with the movement of the beams by adjustment of the 75 spreader arch, when the set screws 40^a, which hold the collars 40 to the horizontal portions of the arches 37, are loosened.

Rigidly secured on the standards 15, and preferably in the same plane and parallel 80 with the bar 17, is a bar 53 having perforations *d* in each end; in order to relieve the driver of the necessity of holding the wheels 10 against swinging particularly when the machine is being moved from place to place, 85 the rods 18 can be disconnected from the bar 17 and their ends secured in the perforations *d*, of the bar 53; and as the latter is immovable the wheels are held securely 90 against swinging.

To raise or lower the beams 35 individually, or collectively we employ the following mechanism; secured on the frame bar 2 are bearings *e*, *f*, *g*, and *h*; supported in the bearings *f* and *g* are the ends of a bar 54 95 which is preferably square. Both ends of the bar 54 are bored to admit the reduced ends of bars 55 and to form bearings therefor; the bars 55 rock in the bearings *e* and *h*, and have that part of their length outside of the bearings *e* and *h* bent at a right angle to form arms *j* extending toward the front of the machine and curved downwardly; collars 56 are secured on the bars 55 inside the bearings *e* and *h* against which 100 they contact to prevent longitudinal movement of the bars 55. The free ends of the arms *j* are perforated for engagement of the hook ends of links 57 which extend downwardly through members 58 secured on the 105 outer beams 35, and are secured against withdrawal therefrom by cotters in the ends of said links and below the members 58; coiled springs 59 on the links 57 exert their pressure between the members 58 and pins 110 60 on the links 57.

The ends of the bar 54 project beyond the bearings *f* and *g* and have mounted rigidly upon them double sectors 61; on the inner ends of the bars 55 are rigidly secured hand levers 62 provided with the usual form of latch to engage with notches on the adjacent side of the sectors 61; similar levers 62^a are loosely mounted on the ends of the bar 54, and have similar latches 120 to engage with notches in the adjacent side of the sectors 61. The levers 62^a are provided with arms *k*, similar to the arms *j*, and to which are connected links 63 which extend downwardly through members 64 on 125 130

the inner beams 35; the links 63 have coiled springs 65 which exert their pressure between the members 64 and pins 65^a on the links 63, the latter being held against withdrawal from the members 64 by pins or cotter pins in the ends of the links below the members 64. A master lever 66 is rigidly mounted on the bar 54 and is provided with a common form of latching device to engage 10 with notches in a segment 67 secured to the frame bars 2 and 6.

The lever mechanism just described is for the purpose of raising and lowering the beams 35 individually by operation of the lever 62 connected therewith through the links 57 and 63, the desired position of the beams 35 when raised or lowered being fixed by the latches on the levers 62 engaging with notches in the sectors 61; as previously stated the sectors 61 and the master lever 66 are rigidly mounted on the bar 54, it will therefore be apparent that when the levers 62 are held by engagement of their latches with the sectors 61, the beams 35 25 can be raised simultaneously by operation of the master lever 66 and held in a raised position by the latch on the lever 66 engaging with a notch in the segment 67.

A segment 68, substantially horizontal is 30 provided with forwardly extending parallel arms 69 and 70 connected by an arched rib 71 and which is preferably integral therewith; the arms 69 and 70, have slots 72 therein to admit the bars 17 and 53 which 35 support the segment 68 and on which the latter is adapted to lateral movement, the slots 72 being sufficiently large for that purpose. Pivotaly supported intermediate its length on the underside of the arched rib 40 71 is a hand lever 73 which is provided with the usual form of latch to engage with the notches in the segment 68; the lever 73 has pivotally connected to its forward end a rod 74 which is extended laterally and connected to an arm 75 rigidly secured on one 45 of the arches 37. Pivoted intermediate its length on the upper side of the rib 71 is a hand lever 76 having a latch to engage with notches in a segment 77 similar to the 50 segment 68 and parallel therewith; the segment 77 is secured to the arms 69 and 70 by bolts or rivets 6. A rod 78 is pivotally connected to the forward end of the lever 76 and extends in the opposite direction from 55 the rod 74 and is connected to an arm 79 rigidly mounted on the other arch 37. By operating the levers 73 and 76 the two groups of beams 35 connected to the arches 37 and 48^a are adjusted toward or from each 60 other, the arches 37 swinging on the supporting rods 38 and their tops moving in forked guides 37^a rigidly secured to the bars 4 and 7.

As shown in the drawings, particularly in 65 Figs. 1 and 3, the segments 68 and 77 are

secured to the sliding bar 17 by pins or cotter pins 17^a inserted in perforations in the arms 69 and 70 and the sliding bar 17, and the levers 73 and 76 are locked to the segments 68 and 77, so that if the foot levers 28 and 70 31 are operated to swing the wheels 10 the arches 37 and 48^a will be simultaneously moved in the same direction, yet it will still be possible to adjust either group of beams independently by operation of the levers 73 75 and 76. If it is desired however to separate the adjustment of the wheels and the groups of beams 35, the cotter pins 17^a are withdrawn from the arms 69 and 70 and the sliding bar 17 and inserted in perforations 80 in the forward ends of the arms 69 and 70, and through similar perforations in the bar 53, so that the wheels can be swung without affecting the position of the groups of beams 35, the latter still being capable of lateral 85 adjustment by operating the levers 73 and 76; when the rods 18 are disconnected from the sliding bar 17 and connected to the bar 53 the wheels are held against adjustment by operation of the foot levers 28 and 31, and 90 if the arms 69 and 70 are also secured to the bar 53 it is evident that the groups of beams 35 only are capable of adjustment.

The coiled springs 42, as shown and described, are connected to the forward parts 95 of the beams 35 rearward of the pivotal connections of the latter to the arches 37, and are also connected to the upper portions of the rods 38 instead of to the frame as has been customary heretofore; by attaching the 100 springs 42 to the upper portions of the rods 38, the tension of the springs 42 in balancing the beams 35 is not increased when the arches 37 are moved laterally, the rods 38 swinging laterally with them and carrying 105 the springs 42 so that the relative position of the latter to the beams 35 and the rods 38 remain unchanged during the lateral movement of the arches and beams.

From the foregoing description it will be 110 apparent that my improved cultivator is capable of a wide range of adjustment to suit any condition of crops grown in rows.

What I claim is—

1. A cultivator having a frame, supporting wheels therefor, a laterally movable element with which said wheels are connectible for simultaneous adjustment angularly to the frame, a rigid element with which said wheels are connectible to hold them non-adjustable, foot levers pivotally supported on the frame and connected with the laterally movable element and operable to actuate the latter, gangs of cultivating devices movably supported on the frame and connectible at 115 will to the laterally movable element for adjustment simultaneously with the adjustment of the wheels and adjustable laterally with said element when the wheels are connected with the rigid element, said cultivat- 120 125 130

- ing devices adapted to be disconnected from the movable element and connected to the rigid element whereby the wheels only are adjustable by the laterally movable element 5 when connected therewith.
2. A cultivator having a frame, supporting wheels therefor, a sliding bar mounted in bearings on the frame, a rigid bar mounted on the frame, rods connecting the sliding 10 bar with the wheels, foot levers pivotally supported on the frame and connected with the sliding bar and operable to move the latter to adjust the wheels angularly to the frame to vary the direction of travel of the 15 cultivator, said rods adapted to be disconnected from the sliding bar and connected to the rigid bar to hold the wheels against adjustment, gangs of cultivating devices supported on the frame and connectible at 20 will to the sliding bar for adjustment simultaneously with the wheels and in the same direction and adjustable with the sliding bar when the wheels are connected with the rigid bar, said cultivating devices adapted 25 to be disconnected from the sliding bar and connected to the rigid bar whereby the wheels only are adjustable by the sliding bar when the latter is connected therewith.
3. A cultivator having a frame, supporting 30 wheels therefor, a sliding bar mounted in bearings on the frame, a rigid bar secured on the frame parallel to the sliding bar, rods extending substantially in alinement with the sliding bar and connecting the sliding 35 bar with the wheels, foot levers pivoted on the frame and connected to the sliding bar and operable to adjust the wheels angularly to the frame to vary the direction of travel of the cultivator, said rods adapted to be 40 disconnected from the sliding bar and connected to the rigid bar to hold the wheels non-adjustable, laterally movable arches supported on the frame, and levers manually operable to move said arches toward or from 45 each other or in the same direction independent of the wheel adjustment.
4. A cultivator having a frame, supporting 50 wheels therefor, a sliding bar mounted in bearings on the frame, a rigid bar secured on the frame parallel to the sliding bars, rods extending substantially in alinement with the sliding bar and connecting the sliding 55 bar with the wheels, foot levers pivoted on the frame and connected to the sliding bar and operable to adjust the wheels angularly to the frame to vary the direction of travel of the cultivator, arches movably supported on each end of the frame, gangs of cultivating devices carried by the arches and 60 hand levers operable to move said arches toward or from each other or in the same direction, said rods adapted to be disconnected from the sliding bar and connected to the rigid bar to hold the wheels nonadjustable, 65 and the foot levers actuatable to move the

arches simultaneously toward either side of the cultivator.

5. A cultivator having a frame, supporting wheels therefor, a sliding bar mounted in bearings on the frame, a rigid bar secured 70 on the frame parallel to the sliding bar, arches movably supported on each end of the frame, gangs of cultivating devices carried by the arches, toothed segments adapted to be secured to the sliding bar, hand levers 75 pivoted intermediate their ends on said segments and connected with arches and operable to move the latter to or from each other or in the same direction, rods extending substantially in alinement with the sliding bar 80 and connecting said sliding bar with the wheels and adapted to be disconnected from the sliding bar and connected to the rigid bar, foot levers pivoted on the frame and connected to the rigid bar, foot levers pivoted 85 on the frame and connected to the sliding bar and operable to move the latter to adjust the wheels angularly to the frame to vary the direction of travel of the cultivator, and actuatable to move the segments and hand 90 levers only and the arches connected therewith when said rods are connected with the rigid bar.

6. A cultivator having a frame, supporting wheels therefor, a sliding bar mounted 95 in bearings on the frame, a rigid bar secured on the frame parallel to the sliding bar, toothed segments secured on the sliding bar and adapted to be disconnected therefrom and connected to the rigid bar, arches movably supported on the frame, gangs of cultivating devices carried by the arches, hand levers pivotally mounted on the segments and connected with said arches to move the latter to or from each other or in the same 100 direction, rods extending substantially in alinement with the sliding bar and connecting the sliding bar with the wheels, and foot levers pivoted on the frame and connected to the sliding bar and actuatable only to adjust 105 the wheels angularly to the frame to vary the direction of travel of the cultivator when the segments and hand levers are secured to the rigid bar.

7. A cultivator having a frame, supporting 115 wheels therefor, a sliding bar mounted in bearings on the frame, rods extending substantially in alinement with the sliding bar and connecting the latter with said wheels, arches movably supported on each 120 end of the frame, toothed segments adapted to be secured to the sliding bar, hand levers pivoted intermediate their ends on said segments and operable to move said arches toward and from each other or in the same direction and foot levers pivotally supported on the frame and connected with the sliding bar and operable to move the latter to adjust the wheels angularly to the frame to vary the direction of travel of the cultivator, and 125 130

to simultaneously move the hand lever bodily to adjust the arches in the same direction as the adjustment of the wheels.

8. A cultivator having a frame, supporting wheels therefor, a sliding bar mounted in bearings on the frame and connected with the wheels, rods extending substantially in alinement with the sliding bar and connecting the latter with said wheels, arches mov-
5 ably supported on each end of the frame, toothed segments adapted to be secured to the sliding bar, hand levers pivoted intermediate their ends on said segments and operable to move said arches toward and
10 from each other or in the same direction, and foot levers pivotally supported on the frame and connected with the sliding bar and operable to move the latter to adjust the wheels angularly to the frame to vary
15 the direction of travel of the cultivator, and to simultaneously move the hand levers bodily to adjust the arches in the same direction as the adjustment of the wheels, said hand levers being operable to move the
20 arches irrespective of the foot levers.

9. A cultivator having a frame, supporting wheels therefor, a sliding bar mounted in bearings on the frame, rods connecting the sliding bar with the wheels, foot levers
30 pivotally supported on the frame and connected with the sliding bar and operable to move said sliding bar to adjust the wheels angularly to the frame to vary the direction of travel of the cultivator, gangs of culti-
35 vating devices supported on the frame and movable laterally and connectible at will to the sliding bar whereby as the latter is moved by the operation of the foot levers to angle the wheels the gangs are adjusted
40 simultaneously in the same direction.

10. A cultivator having a frame, supporting wheels therefor, a sliding bar mounted in bearings on the frame, rods connecting the sliding bar with the wheels, foot levers
45 pivotally supported on the frame and connected with the sliding bar and operable to move the latter to adjust the wheels angularly to the frame to vary the direction

of travel of the cultivator, said rods adapted to be disconnected from the sliding bar and connected to the rigid bar to hold the wheels against adjustment, gangs of cultivating devices supported on the frame and movable laterally and connectible at will to the sliding bar whereby the gangs are moved simul-
55 taneously in the same direction when the wheels are non-adjustable.

11. A cultivator having a frame, supporting wheels therefor, a sliding bar mounted in bearings on the frame, rods connecting the sliding bar with the wheels, foot levers pivotally supported on the frame and connected with the sliding bar and operable to move the latter to adjust the wheels angularly to the frame to vary the direction of travel of the cultivator, gangs of cultivating devices supported on the frame and movable laterally, hand levers operable to adjust said gangs toward or from each other, and a support for the hand levers
60 connectible at will to the rigid bar whereby the gangs are adjustable by the hand levers only, and the wheels only are adjustable by the foot levers.

12. A cultivator having a frame, supporting wheels therefor, front arches at each end of the frame, beams having cultivating devices and pivotally supported on the lower portions of said arches, supports for said arches pivotally connected to the ends thereof and to the main frame, coiled springs connected to said beams adjacent their forward ends and to the arch supports adjacent the frame, and a lever mechanism on the frame and connected with the front arches
70 80 85 and operable to move said arches toward and from each other or in the same direction without altering the tension of said springs.

In testimony whereof I affix my signature
in presence of two witnesses.

JOHN V. HOLSTEIN.
